UNITED STATES PATENT OFFICE.

HENRY SCHUMACHER, OF BUFFALO, NEW YORK.

APPLICATOR.

Application filed July 18, 1921. Serial No. 485,688.

To all whom it may concern:

Be it known that I, HENRY SCHUMACHER, a citizen of the United States, residing in Buffalo, in the county of Erie and State of New York, have invented new and useful Improvements in Applicators, of which the following is a specification.

This invention relates to an applicator which is more particularly designed for applying material, such as a medicated salve or powder to parts of the body of a person which are difficult of access by the use of the person's own hands only and without the aid of another person, particularly the back of the body, which can only be reached ordinarily with difficulty without the use of special means. It is to be understood however, that this device can be used for other purposes, where it is desired to apply a material evenly and conveniently from a supply receptacle or reservoir to a surface intended to receive the material.

It is the object of this invention to provide a device of this character which will permit of applying to the surface to be treated various kinds of materials either in a powder or in a semi-fluid condition and to discharge this material, if desired, under pressure to the face of the device whereby the same is rubbed or spread over a surface intended to receive the same and also to permit of regulating the discharge of the material, as required. A further object of this invention is to so construct a device of this character that the same can be readily filled with the material to be applied, which can be thoroughly and easily cleaned and which is not only convenient in use but permits ordinarily inaccessible parts of the body to be easily reached and applying material thereto.

In the accompanying drawings:

Figure 1 is a longitudinal section of one form of applicator embodying my invention. Figure 2 is a top plan view of the same. Figures 3 and 4 are horizontal sections taken on the correspondingly numbered lines in Fig. 1 and looking in the direction of the arrows associated with these lines.

Similar characters of reference refer to like parts throughout the several views.

The receptacle or reservoir intended to contain a supply of material which is to be applied to a surface of the body or elsewhere, may be variously constructed, but as

shown in the drawings the same comprises a tubular or circular body or wall 10 which is closed at its upper end by a tight upper head 11 while its lower end is closed by means of a removable head which is detachably connected with the body 10.

As shown in Fig. 1, this lower head, in its preferred form, comprises a lower or outer disk 12 having an upwardly projecting marginal flange 13, so that the same is of downwardly dished form, and an annular rim 14 projecting laterally from the upper edge of the flange 13 and engaging with the lower edge of the tubular body or wall 10. The lower head is detachably connected with the body 10 by means of a clamping ring having a screw threaded rim 17 which engages with the corresponding screw thread on the lower end of the body 10 and is provided at its lower end with an inwardly projecting flange 18 which engages against the underside of the rim 14 of the lower head. Above the outer or lower disk is arranged an upper disk 15 which is provided with a downwardly or outwardly projecting flange 16 at its margin and is arranged within the flange 13 of the lower disk and serves to space the lower disk 12 and the upper disk 15 apart so as to form a chamber between the same.

A plurality of bunches of bristles 19 extend at their upper ends through openings formed in the lower or outer disk 12 and are secured in place by means of a filling 20 of cement which is arranged within a chamber or space between the lower and upper disks 12, 15, and surrounds the upper ends of the bristles therein, so that these bristles are firmly secured to the lower head of the receptacle and will not become loose or detached when rubbing or brushing the outer ends of the bristles over the surface to which the treating material is applied. This treating material is conducted from the interior of the receptacle to the underside of the lower head at the base of the bristles by means of a plurality of ducts, conduits, or openings extending through the lower head. These ducts are preferably constructed in the form of short sleeves or nipples 21, each of which extends vertically across the space between the lower and upper disks 12, 15 and has its lower and upper ends arranged in corresponding openings formed in said lower and upper disks and is secured in place by upsetting or riveting the lower end of the nipple against the underside of the

lower disk 12 while its upper end is upset or riveted against the upper side of the upper disk 15.

The flow or discharge of the material from the receptacle or reservoir through the discharge nipples 21 to the base of the bristles may be regulated in accordance with the requirements, this being preferably effected by the means which are shown in Figs. 1 10 and 3 of the drawings and which comprise a rotatable shutter 25 of disk form which is pivoted upon the inner side of the lower head of the receptacle and provided with an annular row of openings 27 which are 15 adapted to be moved into or out of registration with the passages of the nipples 21 for the purpose of either fully uncovering these outlet passages, or fully covering the same, as well as permitting of particularly un- 20 covering these nipples so as to regulate the amount of material which can escape from the receptacle as desired. This shutter is preferably provided with a finger piece 26 at one edge thereof, whereby the same may 25 be turned to adjust the position of the shutter or valve 25 when the lower head of the receptacle is removed from the body.

The preferred means for pivotally connecting this shutter with the lower head 30 which are shown in Figs. 1, 3 and 4 comprise a pivot sleeve or bearing 37 extending across the space between the disks 12 and 15 and secured at its opposite ends thereto by riveting, and a pivot pin or rivet 28 ex- 35 tending through the bearing sleeve 37 and a separate opening in the shutter 25, and fitted sufficiently close so as to hold the shutter or valve 25 tight against the upper ends of the nipples or tubes 21 and prevent any 40 leakage between the same.

After discharging a quantity of material from this receptacle to the bristles of the brush this material may be spread evenly over the surface to be treated and also 45 rubbed into the surface for curative purposes, as for instance when applying salve or medicine to an affected part of the body. The discharge of this material, particularly when the same is in the form of a powder 50 or a salve, is preferably accomplished as often as required by means of pressure applied to the same within the receptacle. Any approved means may be employed for effecting this pressure, for example, as 55 shown in Fig. 1, this may be accomplished by means of a tube 22 of flexible rubber or other suitable material, having its outer end connected with the upper part of the reservoir and an air forcing or compressing de- 60 vice such as a bulb 23 connected with the tube 22. By pressing on this bulb, which is constructed with a valve mechanism similar to that commonly employed in connection with atomizers and similar spraying 65 devices, an air pressure is produced upon

the material within the receptacle which causes the same to flow from the latter through the outlet openings 21 and to the bristles 19 where the same is applied or rubbed over the surface to be treated.

In order to permit an individual to use this applicator by himself without the aid of any other person and applying a medicine or other material to parts which are not easily accessible by the use of the hands, only, such as the small of the back, a handle 24 of sufficient length is provided, which is connected at its front end with the body of the reservoir or other part thereof, while its rear end is adapted to be grasped by the hand of the operator and thus permit of reaching the parts which ordinarily are inaccessible or difficult of access.

The receptacle may be readily filled with a new supply or charge of material by removing the lower head from the body, and while thus removed the parts may also be thoroughly cleaned and disinfected and thus enable the same instrument, if desired, to be used either with different medicines or preparations and also used on different persons in accordance with the treatment and the character of the medicines or other materials which are to be applied to the respective persons.

I claim as my invention:

1. An applicator having a receptacle adapted to receive the material to be applied and comprising a tubular body and a head arranged at the front end of said body, said head having outer and inner disks which are spaced apart, ducts extending through said disks, bristles extending through said outer disk into the space between the same and the inner disk, and a filling of cement arranged between said disks and securing the inner end of the bristles therein.

2. An applicator having a receptacle adapted to receive the material to be applied and comprising a tubular body and a head arranged at the front end of said body, said head having outer and inner disks which are spaced apart, ducts extending through said disks, bristles extending through said outer disk into the space between the same and the inner disk, a filling of cement arranged between said disks and securing the inner end of the bristles therein, and a rotary shutter pivoted within the receptacle and having openings adapted to register with said ducts.

3. An applicator having a receptacle adapted to receive the material to be applied and comprising a tubular body and a head arranged at the front end of said body, said head having an outer disk provided with an inwardly projecting flange and an inner disk provided with an outwardly projecting flange which is arranged

within the flange of the outer disk, ducts extending through both of said disks, bristles extending through said outer disk and into the space between the outer and inner disks, 5 and a filling of cement arranged between said disks and securing the bristles therein.

4. An applicator having a receptacle adapted to receive the material to be applied and comprising a tubular body and 10 a head arranged at the front end of said body, said head having an outer disk provided with an inwardly projecting flange and an inner disk provided with an out-

wardly projecting flange which is arranged within the flange of the outer disk, ducts extending through both of said disks, bristles extending through said outer disk and into the space between the outer and inner disks, 15 a filling of cement arranged between said disks and securing the bristles therein, a pivot sleeve extending centrally through said disks, a rotary shutter arranged within the receptacle and having openings adapted to register with said ducts, and a pivot extending through said sleeve and shutter.

HENRY SCHUMACHER.
